FRANK W. CALDWELL, OF DAYTON, OHIO

COOLING FAN

Application filed November 3, 1921. Serial No. 512,408.

This invention relates to fans and more particularly to a cooling fan for an automobile engine.

The greatest need for the cooling fan for an automobile engine occurs when the automobile is moving at a relatively slow speed with the engine under a heavy load, as when the car is climbing a hill on high gear. When the automobile is running at a relatively high speed enough air flows through the radiator, as a result of the speed of the automobile, to provide sufficient cooling for the engine. Inasmuch as the fan absorbs a great deal of power it is desirable that it should be so controlled as to save this power when the fan is not needed for cooling purposes.

One object of the invention is to provide a fan of such a character that when the automobile is moving at such a speed that the fan is not required for cooling purposes it will absorb little or no power from the engine.

It is a further object of the invention to provide such a fan in which the blade angles of the fan will be automatically altered, when the automobile reaches a certain predetermined speed, to cause the fan to operate as a wind mill, so that no engine power is required to operate it.

A further object of the invention is to provide a fan of this kind which will be simple in its construction and operation and which may be easily maintained in an operative condition.

Other objects of the invention will appear as the device is described in detail.

In the accompanying drawings Fig. 1 is an end view of a fan embodying my invention; Fig. 2 is a sectional view taken centrally through the hub of such a fan; Fig. 3 is a transverse section taken on the line 3—3 of Fig. 2; Fig. 4 is a diagrammatical view showing a section of a fan blade in its normal position; Fig. 5 is a similar view showing the section of the fan blade in its reverse position; and Figs. 6 and 7 are diagrammatical

views illustrating the action of centrifugal force on the blade.

In these drawings I have illustrated one embodiment of my invention and have shown the same as comprising a fan in which each of the blades is mounted for movement about an axis extending lengthwise of the blade. The movement of the blades about their respective longitudinal axes is controlled by a suitable yielding device which will retain them in their normal, or operative, positions until the engine has reached a predetermined speed and which will then permit them to rotate about said longitudinal axes into positions which will so alter the blade angles as to cause the same to operate as a wind mill. It will be understood that the particular embodiment here illustrated has been chosen for the purpose of illustration only and that the fan itself may take various forms and the details of construction may be widely varied from those here shown.

In that particular form of the device here illustrated the fan comprises a rotatable supporting structure, or hub, 1, which is journaled in a bearing 2 and may be operatively connected with a source of power, such as an automobile engine, in any suitable manner. Mounted on this hub are one or more fan blades 3, the present fan having four, and each of these blades is rotatable about an axis extending lengthwise thereof. To this end each blade is provided at its inner end with a trunnion 4 which is journaled in a suitable bearing in the supporting structure, or hub, 1. As here shown, the supporting structure is hollow, or cup shaped, and the trunnions extend through the wall thereof and are secured in position in their bearings by collars 5 rigidly secured to the inner ends thereof. If desired, antifriction bearings 6 may be interposed between the collars and the hub structure to reduce the frictional contact between these parts.

Suitable means are provided for holding

the blades normally against rotation and thus maintaining the same in their operative positions, in which they will act as fan blades. In the present construction, a stud, or shaft, 7 is rigidly secured to and may, if desired, be formed integral with the supporting structure. This stud is arranged centrally of the supporting structure and has rotatably mounted thereon a sleeve 8 having at its outer end a circumferential flange 9 in which are provided a plurality of recesses 10, there being one such recess for each blade. The inner end of the sleeve is recessed, as shown at 11, and the end walls of this recess serve as stops which cooperate with a fixed stop, or lug, 12, carried by the end wall of the hub structure and extending into the recess. Each fan blade is connected with the sleeve so that the rotation of the fan blades about their longitudinal axes will impart rotatory movement to the sleeve. As here shown, the collar 5 of each blade has rigidly secured thereto an arm 13, the outer end of which extends into the corresponding recess 10 in the flange of the sleeve. Preferably the outer ends of the arms 13 are spherical to reduce the frictional contact between the same and walls of the recesses. The sleeve, and consequently, the blades are held normally against rotatory movement by means of a spring 14 which is coiled about the outer end portion of the stud, or shaft, 7 and has one end secured to the sleeve and the other end secured to a collar 15 which is rigidly secured to the stud, or shaft, 7. The tension of the spring may be regulated by adjusting the collar 15 on the stud 7 and to this end the collar is screw threaded onto the stud and then secured against rotation by means of a pin 16.

In the present construction centrifugal force is utilized to rotate the fan blades about their longitudinal axes and thus alter the blade angles. The action of the centrifugal force on the blade may be explained by reference to Figs. 4 and 7. Fig. 4 shows the air force acting on a section of an ordinary fan blade and it will be apparent that the air pressure on the blade is such as to resist the revolution of the fan. In Fig. 5 the angle between the blade section of the fan and the plane of revolution has been reduced to such an extent that the air pressure will be substantially reversed and will cause the fan to function as a wind mill. With the blade in the position shown in Fig. 5 it will be apparent, therefore, that the air flowing through the radiator of an automobile moving at high speed will assist the revolution of the fan to such an extent that little or no power will be required to operate the same.

As has been stated, centrifugal force is utilized to so alter the blade angles and in Fig. 6 I have shown a plan view of a typical fan blade which may be considered as di-

vided along its longitudinal center into two halves and the centers of gravity of the respective halves may be taken as C and D. The centrifugal force on that portion of the blade whose center of gravity is at C acts in a radial direction and may be taken as equal to C—E. It is evident that it will have a component C—A which acts in a direction perpendicular to the center line of the fan blade. Likewise, the centrifugal force of that portion of the blade whose center of gravity is at D acts in a radial direction and may be taken as equal to D—F, and will have a component D—B which is perpendicular to the center line of the blade. If these components are now transferred to the sectional view in Fig. 7 it will be obvious that they act upon the respective portions of the blade in opposite directions and thus tend to produce a twisting movement which will reduce the angle between the blade section and the plane of revolution. This twisting movement is produced by the centrifugal force and is proportional to the square of the revolutions. Obviously as the speed of the engine increases the centrifugal force on the fan blades will increase until when the automobile reaches a speed at which the fan is no longer necessary for cooling purposes the twisting action of the centrifugal force on the blades will be sufficient to overcome the tension of the spring 14, thus permitting the blades to move from the position shown in Fig. 4 to the position shown in Fig. 5 and converting the fan into a wind mill which will be operated by the flow of air through the radiator, thereby greatly reducing, or entirely eliminating, the absorption of power by the fan from the engine. When the blades have moved to the desired position their further rotation is prevented by the stop 12, and as the speed of the engine falls the blades will be returned to their normal positions by the action of the spring 14, the movement in this direction also being limited by the stop 12.

While I have shown and described one embodiment of my invention I wish it to be understood that I do not desire to be limited to the details thereof as various modifications may occur to a person skilled in the art.

Having now fully described my invention what I claim as new and desire to secure by Letters Patent, is:

1. In a fan, a rotatable supporting structure, a blade mounted on said structure for movement by the action of centrifugal force thereon about an axis extending lengthwise of said blade and held against longitudinal movement, a member rotatable with relation to said supporting structure about an axis extending transversely to said axis of said blade, an operative connection between said blade and said member, and a spring acting

- on said member to resist its rotation by said blade.
2. In a fan, a rotatable supporting structure, a blade mounted on said structure for movement by centrifugal force about an axis extending lengthwise of said blade, a stud carried by said supporting structure, a member rotatably mounted on said stud, an operative connection between said member and said blade, and a spring coiled about said stud and connected at one end with said member and at the other end with said stud. 70
3. In a fan, a rotatable supporting structure, a blade mounted on said structure for movement by centrifugal force about an axis extending lengthwise of said blade, a stud rigidly secured to said supporting structure, and extending transversely to the axis of said blade, a part rotatably mounted on said stud and having a recess therein, an arm extending radially from said blade and having one end arranged in said recess, and a spring coiled about said stud and connected at one end with said part and at the other end with said stud. 75
4. In a fan, a rotatable supporting structure, a blade mounted on said structure for movement by centrifugal force about an axis extending lengthwise of said blade, a stud rigidly secured to said supporting structure, and extending transversely to the axis of said blade, a part rotatably mounted on said stud and having a recess therein, an arm extending radially from said blade and having one end arranged in said recess, and a spring coiled about said stud and connected at one end with said part and at the other end with said stud. 80
5. In a fan, a hollow supporting structure having an axial stud rigidly secured thereto, a plurality of fan blades mounted on said supporting structure for movement about axes extending lengthwise of the respective blades, a sleeve rotatably mounted on said stud and having at one end a flange provided with recesses, an arm rigidly secured to each blade and having its end extending into one of said recesses, a stop to limit the rotation of said sleeve, and a spring coiled about said stud and having one end connected with said sleeve and the other end connected with said stud. 85
6. In a fan, a rotatable supporting structure, a blade mounted on said structure for movement about an axis extending lengthwise of said blade, a stud carried by said supporting structure, a member rotatably mounted on said stud, an operative connection between said member and said blade, and a spring acting on said member to resist its rotation by said blade. 90
7. In a fan, a rotatable supporting structure, a blade mounted on said structure for movement about an axis extending length- 95
- wise of said blade, a stud rigidly secured to said supporting structure and extending transversely to the axis of said blade, a part rotatably mounted on said stud and having a recess therein, an arm extending radially from said blade and having one end arranged in said recess, and a spring coiled about said stud and connected at one end with said part and at the other end with said stud. 100
8. In a cooling fan for an automobile engine, a fan blade mounted for bodily movement about an axis extending transversely thereto and for movement about a longitudinal axis located between the lateral edges thereof and in such relation to the mass of said blade that the movement of said blade about said transverse axis will cause it to move about said longitudinal axis in a direction to decrease the angle thereof as the speed of movement about said transverse axis increases, and means to restore said blade to its initial position with relation to said longitudinal axis. 105
9. In a cooling fan for an automobile engine, a fan blade mounted for bodily movement about an axis extending transversely thereto and for movement about a longitudinal axis located between the lateral edges thereof and in such relation to the mass of said blade that the movement of said blade about said transverse axis will cause it to move about said longitudinal axis in a direction to decrease the angle thereof as the speed of movement about said transverse axis increases, and means acting on said blade to hold the same against movement about said longitudinal axis until the movement about said transverse axis reaches a predetermined speed. 110
10. In a cooling fan for an automobile engine, a fan blade held against longitudinal movement and mounted for bodily movement about a transverse axis and for movement about a longitudinal axis located between the lateral edges thereof and in such relation to the mass thereof that the action on said blade of centrifugal force resulting from the movement thereof about said transverse axis will cause said blade to move about said longitudinal axis in a direction to decrease the angle thereof as the speed of movement about said transverse axis increases, and yieldable means to resist the movement of said blade about said longitudinal axis. 115
11. In a cooling fan for an automobile engine, a fan blade held against longitudinal movement and mounted for bodily movement about a transverse axis, and for movement by the action of centrifugal force thereon about a longitudinal axis in a direction to decrease the angle thereof as the speed of movement about said transverse axis increases, and means to control the movement of said blade about said longitudinal axis. 120
12. In a cooling fan for an automobile en- 125

gine, a rotatable supporting structure, a fan
blade mounted on said structure for move-
ment with relation thereto, by the action of
centrifugal force on said blade, about a longi-
5 tudinal axis in a direction to decrease the
angle thereof as the speed of rotation of said
supporting structure increases, and means for
holding said blade against movement about
said longitudinal axis until said supporting
10 structure is rotated at a predetermined speed.

10 In testimony whereof, I affix my signature
hereto:
